UNITED STATES PATENT OFFICE.

GEORGE L. PEABODY, OF PITTSBURG, PENNSYLVANIA.

REINFORCING CONCRETE CONSTRUCTION.

No. 832,557.

Specification of Letters Patent.

Patented Oct. 2, 1906.

Application filed October 31, 1904. Serial No. 230,844.

To all whom it may concern:

Be it known that I, GEORGE L. PEABODY, a citizen of the United States, residing at Pittsburgh, in the county of Allegheny and State of Pennsylvania, have invented certain new and useful Improvements in Reinforcing Concrete Constructions, of which the following is a specification, reference being had therein to the accompanying drawings, forming part 10 of the specification, in which—

Figure 1 is a vertical longitudinal sectional view on the line I I of Fig. 2, showing my improved reinforcing construction incorporated with a girder of a building. Fig. 2 is a 15 partial plan view of the floor construction, showing embodiment therewith of my improvement. Fig. 3 is a sectional view at right angles to Fig. 1, indicated by the line III III of Fig. 2. Fig. 3^a is a detail view of a 20 portion of one of the main bars. Fig. 4 is a sectional view showing a modified arrangement. Fig. 5 is a plan view of Fig. 4, showing the interlacing engagement of the terminals of the reinforcing elements. Fig. 6 25 is a detail view showing a further modification. Fig. 7 is a detail view showing a modified construction of the tension member. Fig. 8 is a detail view showing a skeleton 30 ferrule for joining column members. Fig. 9 is a sectional detail view illustrating a modification.

My invention refers to improvements in reinforced building construction of concrete, cement, &c., and refers particularly to the 35 construction and arrangement of the metallic elements constituting the reinforcement, the objects in view being to so arrange and distribute the various elements as to counteract the various strains in different directions 40 to form a continuous anchoring construction. I employ a series of longitudinal wires or rods constituting main frames, with which are rigidly connected supplemental rods or bars adapted to engage a segregated body of the 45 concrete or cement, preferably above the posts or columns or in the body portion of the beams or girders, so as to embrace sections of the concrete and to equalize and distribute the strain thereto from opposite directions in the manner somewhat similar to cantaliver-bridge construction.

Referring to the drawings, 2 represents the posts or columns of a building incorporated with the girders 3, beams 4, and floor 5, made 55 of continuous concrete or cement.

6 represents main strengthening members, as bars, which are embedded longitudinally in the lower portions of the beams and girders, with which are rigidly connected in any suitable manner at 7 the upwardly-extending wires or rods 8. The bars 6 are preferably provided with series of notches *a* at each side, adapted to receive the wires or rods. These wires or rods are set into the notches and are preferably made of considerable 65 length and are separated above the rods 6, as shown, and then crossed in opposite directions, so as to embrace between them a concrete section 9, of wedge, key, or other form, of the beam or girder, the rods being extended horizontally, as shown, through the floors 5 to the next beam or girder, where the same construction is duplicated, and so on throughout the building. An especial advantage of this arrangement is that the weight of the 70 floor is supported by the horizontal rods acting as tension members, and the strain constantly tends to tighten the engagement of the rods with the concrete rather than to pull it apart. As shown in Figs. 1, 2, and 3, 75 the rods constitute a continuous network throughout the length and breadth of the floor, while the wedge or keystone sections 9 are embraced at intervals along the entire 80 length of all of the beams or girders. The 85 upwardly-extending members 8 are preferably arranged slantingly and disposed in a manner best adapted to cross the lines of probable fracture, (indicated at *a a*), as is usually practiced in this type of construction. 90

In Figs. 4 and 5 I have shown some of the reinforcing members arranged in the manner just described, other being connected to the main bar 6, extended upwardly through the beam or girder, preferably diverging, and 95 then extended in a horizontal direction straight ahead through the floor-body across the next cross-beam, girder, or column and beyond to the other side. The reinforcing members of the other side are similarly extended over in a reverse direction and interlaced between the first-described terminals, as shown in Fig. 5, thus providing above the column or beam a closely-assembled series of holding - terminals, as clearly shown. By 100 this construction the various elements are thoroughly distributed throughout the structure, crossed at intervals, and well adapted to counteract the various strains incident to 105 this type of building construction.

In Fig. 6 I have shown a floor member 10 having supplemental upwardly-extending deflected holding-arms 11, the member 10 being secured to one end of one of the holding elements just described, and it is obvious that by this or any other suitable attachment individual floor-reinforcing devices may be incorporated with the beam or girder ties, which for such application may then be 10 made in short sections. In Fig. 7 I have shown a further modification, wherein the triangular arrangement of the rods is still maintained, the members 8' being deflected upwardly and diverged outwardly, then extended horizontally in opposite directions, but connected by bars or wires 12. By this construction is secured a practically continuous tension element throughout the floor and firmly incorporating it with the beam or 20 girder.

In Fig. 8 is shown a skeleton connecting-ferrule 13, having a flaring upper portion adapted to facilitate the continuous joining of vertical column or post members, which 25 thus abut one upon the other.

The essential feature of improvement of my invention is that the holding elements firmly engage and embrace triangular or other sections of suitable form, around 30 which they are looped or tied in combination with the main anchoring-bar 3, the lateral strains being transmitted thereto from the lighter floor construction, whereby the main elements of the building are best utilized to 35 act as primary supports—i. e., the columns, beams, girders, &c., constitute the main supporting elements upon which the entire structure is carried and to which it is anchored.

40 As shown in Figs. 1 and 4, various of the terminals 14 may be deflected upwardly or downwardly and incorporated with the post, column, or wall structures in a manner which will be readily understood, without detailed 45 description, by those familiar with this class of construction, and the character of the binding elements which I employ is well adapted to their arrangement or application to this construction, as well as that just described. The rods, bars, or wires are of a suitable strength according to the work in view. Their number and arrangement are within the judgment or discretion of the builder or designing architect, and it is obvious 50 that various applications of the invention may be made to suit different requirements and conditions.

The reinforcing elements are placed in position during the progress of the work and 60 previous to or during the insertion of the concrete into the molding apparatus. The elements are sufficiently flexible to be bent in the various directions, and when incorporated in the manner I have shown and described 65 the system will be found to provide

for all of the various strains and conditions arising and incidental to this type of construction.

Having described my invention, what I claim is—

1. Reinforcing construction for concrete, &c., consisting of a main notched bar and a tie element surrounding the bar and in holding engagement with the notches thereof, looped around an anchoring-body of concrete 75 and crossed in opposite directions, substantially as set forth.

2. Reinforcing construction for concrete, &c., consisting of a main notched bar and a tie element surrounding the bar and in holding engagement with the notches thereof, looped around an anchoring-body of concrete 80 and crossed in opposite directions, the terminals of said tie element providing holding extensions, substantially as set forth.

3. The combination with the main portions of a concrete structure, as beams, floor-body, &c., of main notched bars and tie elements surrounding said bars and in holding engagement with the notches thereof, said tie 90 elements being looped around anchoring sections of the concrete and traversing the intervening floor-body, substantially as set forth.

4. The combination with a main reinforcing member provided with series of notches or recesses, of a plurality of tie members surrounding the main member secured thereto by engagement with the notches, and formed into inclosing loops having oppositely-disposed crossed holding portions, substantially 95 as set forth.

5. The combination with a main reinforcing member provided with series of notches or recesses, of a plurality of tie members surrounding the main member secured thereto by engagement with the notches, and formed into inclosing loops having oppositely-disposed crossed holding portions, said loops being arranged slantwise of the main member, substantially as set forth.

6. In concrete construction, the combination with a beam, &c., of main reinforcing members having series of notches or recesses, located at each side of the beam, and provided with rigidly-connected tie members 105 looped around said main members, engaging the notches thereof, and crossed through the beam in opposite directions, substantially as set forth.

7. In concrete construction, the combination with the columns, beams, girders and floor-body of a building, of main notched reinforcing members embedded in the concrete and provided with rigidly-attached tie members in holding engagement with said notches, 115 looped around holding-sections of concrete, crossed in opposite directions and having terminals embedded in the building structure, substantially as set forth.

8. In concrete construction, the combina- 120

- tion with a floor-beam and floor, of a main reinforcing member embedded in the base of the beam provided with series of notches or recesses, and horizontal floor-strengthening members embracing said main members and engaging the notches thereof, crossing horizontally beyond each other and converging toward and surrounding the main reinforcing member, substantially as set forth.
9. In concrete construction, the combination with a floor-beam and floor, of a main reinforcing member embedded in the base of the beam provided with series of notches or recesses, and horizontal floor-strengthening

members embracing said main members and 15 engaging the notches thereof, crossing horizontally beyond each other and converging toward and surrounding the main reinforcing member, said floor members thereby inclosing a triangular section of the beam, substantially as set forth.

In testimony whereof I affix my signature in presence of two witnesses.

GEORGE L. PEABODY.
